HINGE CONSTRUCTION

Sigurd Brantingson, Palisades Park, N. J., assignor to Francis Keil & Son, Inc., a corporation of New York

Application September 7, 1933, Serial No. 688,455

3 Claims. (Cl. 16—131)

This invention relates to hinge construction and more particularly to heavy-duty precision hinge construction and installations.

One of the objects of this invention is to provide a thoroughly practical and inexpensive hinge construction that will be well adapted to meet certain peculiar varying conditions met with in practical use. Another object is to provide a hinge construction that will be of wide adaptability and yet be simple, strong, and durable. Another object is to provide a hinge construction in which such objects as those just noted are dependably achieved while at the same time maintaining simplicity and ease of installation and nicety and neatness of appearance. Another object is to provide a hinge construction of the above-mentioned character which will have, to meet certain varying conditions met with in practice, foolproof and self-locking adjustability.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown one of various possible embodiments of my invention,

Figure 1 is a horizontal sectional view, on a small scale, illustrating a practical installation of my hinge construction;

Figure 2 is an exploded plan view of the various parts making up my hinge construction;

Figure 3 is a vertical sectional view as seen along the line 3—3 of Figure 2, and

Figure 4 is a perspective view on an enlarged scale of one of the parts of the hinge construction.

Similar reference characters refer to similar parts throughout the several views of the drawing.

Referring first to Figure 1 of the drawing, I have there indicated a wall or chamber 10 having an opening therein closed by a door 11; illustratively and as conducive to a clearer understanding of certain features of my invention, the chamber 10—11 might be considered to be a cooling or refrigerating compartment such as is used for the storage of particularly food products and the like and in which of necessity the walls and doors are heavily insulated and are of substantial mass or weight. The door 11 may be of any suitable shape or construction but usually it is

so constructed or shaped that its front face 11a projecting forwardly from the front or outer face 10a of the chamber, the door 11 sometimes having outer peripheral parts, as indicated in Figure 1, that overlap the front face of the chamber wall in order thus to achieve a better sealing or closure of the chamber itself.

The door 11 is hinged to a wall of the chamber 10 by any suitable number of hinges, one of which appears in elevation in Figure 1. In installations of particularly this character, however, there exist such wide variations between the spacing of the planes or faces 11a (of the door 11) and 10a (of the wall of the chamber 10), that either of the hinges to be employed must be specially constructed to take care of the particular offset existing between these planes and thus it is necessary to manufacture or to maintain in stock a complete array of hinges having different offsets, if these varying conditions in practice are to be coped with. Such practice, however, has many disadvantages and one of the dominant aims of this invention is to provide a hinge construction which will meet such varying conditions in practice and achieve other advantages.

Illustratively the hinge construction includes a hinge member 12 (Figures 1 and 2) preferably in the shape of a suitable elongated plate member provided with suitable holes 13 by which it may be secured, as by screws or bolts, to the front face 11a of the door 11; its left-hand portion (Figures 1 and 2) may be of substantial width and preferably is of increased thickness, thus to provide a plurality of eye members of which, for purposes of illustration, four are shown in the embodiment selected for illustration in the drawing; these four eyes (Figure 2) are indicated at 14, 15, 16 and 17, and they are vertically spaced and aligned, having therethrough apertures 14a, 15a, 16a, and 17a, respectively, also aligned, for the ultimate reception of a suitable hinge pin or pintle, such as that shown at 18 (Figure 2).

With the plate-like hinge member 12 attached to the door 11 (Figure 1) there will thus exist a certain spacing, indicated at A in Figure 1 between the axis of the aligned apertures in the eye members 14—15, etc., and the plane 10a of the chamber wall 10.

Secured to the chamber wall 10 is a companion hinge part generally indicated at 19 (Figures 1, 2 and 3) and this part 19, which like the member 12 above described may be made in the form of a casting, has a base plate portion 19a provided

with suitable holes 20, whereby the part 19 may be secured as by screws or bolts to the fixed or stationary wall of the chamber, assuming a position as will appear from Figure 1.

- 5 The central area or portion of the member 19 is increased in thickness as at 19^b (Figures 2 and 3) and, where the coacting hinge member 12 is provided with four eye members as above described, I prefer to provide the hinge member 19
 10 with at least three eye members adapted to be aligned with the eye members of the hinge member 12, so that all of the eye members may receive the hinge pin or pintle 18; but it is to be understood, of course, that the numbers of eye members above-
 15 mentioned or shown in the drawing are illustrative and may be departed from if desired.

Where I employ three eye members on the fixed hinge plate 19, I provide in the latter three vertically aligned holes 19^c, 19^d and 19^e (Figure 3), these holes being threaded, preferably with a thread of relatively small pitch. Into the threaded openings 19^c, 19^d and 19^e are threaded the threaded shanks 21^a, 22^a and 23^a of the stationary eye members 21, 22 and 23, respectively, the outer or right-hand ends of the latter terminating in the eyes 21^b, 22^b and 23^b, the latter in turn being provided with apertures 21^c, 22^c and 23^c, respectively, these apertures being of the same size and shape as those in the eyes 14, 15, etc. of the other hinge member 12.

In Figure 4 is shown in perspective and on enlarged scale one of the eye members related to the fixed hinge plate 19, and a detailed description of that one will suffice for all. Referring then to Figure 4 and assuming that the eye member 21 is there shown, the member 21 is made of a single piece of suitable metal, such as steel, for example, and its shank portion 21^a is cylindrical and of adequate axial length, for purposes described more in detail hereinafter. Its eye portion 21^b is in general of rectangular vertical cross-section thus providing upper and lower faces for coaction with the faces of the eye members 14, 15, etc. of the other hinge member 12 and for coaction with other parts mentioned hereinafter. Like the eye portions of the hinge member 12, the eye portion 21^b (Figure 4) may be exteriorly rounded or curved, preferably concentrically with the cylindrical hole or aperture 21^c that extends transversely through the eye portion 21^b.

Before applying the plate portion 19 to the fixed wall, such as the outer face 10^a of the chamber 10 (Figure 1) I preferably bore or drill as many holes 24 (see now Figure 3) as there are eye members in the plate portion 19, the holes 24 being of larger diameter than the threaded shanks of the eye members 21, 22, etc. and being spaced center to center vertically by the same spacing center as are the threaded eye members 21, 22, etc. These holes 24 thus provide for accommodating the threaded shanks where the latter project rearwardly or to the left of the rear plane of the plate member 19 (see Figure 3).

60 Preferably, however, and in order to insure, when the hinge construction is installed, the drilling or boring of these holes, I provide, integrally formed therewith, rearward cylindrical extensions on the back face of the member 19; these extensions are better shown in Figure 3 at 19^f, 19^g and 19^h, being respectively concentric with the holes 19^c, 19^d and 19^e, and being also threaded. In such case the holes 24 are, of course, of sufficient diameter to allow these rearward extensions to be received therein.

75 I now rotate the eye members 21, 22, etc., each

with relation to the other, so as to bring the spacing A (Figures 3 and 1) between the axes of the pintle-receiving holes 21^c, 22^c, etc., of these eye members and the face 10^a exactly commensurate with the offset between the planes 10^a and 11^a of the parts 10 and 11, respectively (Figure 1), at the same time, of course, alining the axes of the holes 21^c, 22^c, etc.

The above-mentioned fixing of the spacing A by rotating the eye members 21—22, etc., may be accomplished in any suitable manner; preferably I first secure the member 19 to the fixed wall part and then determine the spacing A with the door seated in closed position, holding the member 12 flat against the face of the door. When the proper spacing has just been achieved, the hinge portion 12 may then be secured to the door.

The eye members 21, 22, etc. are now ready to have related thereto the eye members 14, 15, etc. of the other hinge portion 12, the uppermost three eye members of the hinge member 12 transferring the weight of the door 11 to the three eye members 21, 22 and 23, respectively, but preferably through suitable anti-friction or ball bearing members indicated in Figure 2 at 25, 26 and 27, respectively. All of the eye members and bearing members having been alined, the pivot pin, pintle, or bolt 18 is put through all of the alined apertures, and the construction is ready for operation and use.

The hinge pin 18, however, passes through all of the otherwise rotatable eye members 21, 22, etc., of the hinge part 19, and thus each eye member acts, in coaction with the hinge pin 18, to lock another eye member against rotation about the axis of the threaded shank.

Should the offset of the door with respect to the wall be other than that indicated in Figures 1 and 3, each eye member 21, 22, etc. is given the same angular rotation, in multiples of 180°, in one direction or the other, depending upon whether the offset is less or greater, and thus a wide range of different offsets may be taken care of by the same or single hinge construction. Preferably also the pitch of the thread employed on the shanks is relatively small in order that small increments of differences in offsets may be dependably obtained.

It will thus be seen that there has been provided in this invention a hinge construction in which the various objects above noted, together with many thoroughly practical advantages, are successfully achieved. It will be seen that the construction is thoroughly practical, is capable of inexpensive manufacture, and is strong and durable and, moreover, foolproof and reliable. It will also be seen that the construction is well adapted to meet the widely varying conditions met with in practice.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. A hinge construction for doors having varying degrees of offsets with respect to the wall or frame in which they are mounted comprising, in combination, a hinge unit comprising a plate-like member having projecting from the plane thereof a plurality of alined tube-like portions interiorly threaded, each portion having threaded thereinto a threaded shank whose one end termi-

nates in an eye member, the threads of each shank being of the same pitch and the axis of the opening in the eye member extending at right angles to the axis of the threaded shank, whereby, upon rotation of said threaded shanks in increments of 180° the spacing of the axes of the openings of the eye members from a plane of said plate member may be made the same and commensurate with the offset between the door and the wall or frame, and a companion hinge unit adapted to be secured to the door and having hinge pin means for reception in the openings in said eye members and acting also to prevent rotation of the latter and their respective shanks relative to the plate member carrying them.

2. A hinge construction for doors having varying degrees of offsets with respect to the wall or frame in which they are mounted comprising, in combination, a hinge unit comprising a single plate-like member having central portions of greater thickness than marginal portions thereof, said marginal portions being provided with means for securing said member to the wall or frame and said central portions having a plurality of alined threaded openings, and a plurality of eye members each terminating in a threaded shank portion, each threaded opening in said central portion of the plate member receiving a threaded shank portion of an eye member, thereby to form said hinge unit, and said eye members having such a pitch of thread and such a rotational position with respect to each other and said plate member that the axes of the openings in said eye members are alined and are spaced commensurately with the offset of said

door from said frame, and a companion hinge unit having means for securing it to the door and having eye means adapted to be alined with said openings in said eye members, and a hinge pin passing through said eye members and said eye means for pivotally connecting said hinge units and for preventing rotation of said eye members. 5

3. A hinge construction for doors having varying degrees of offsets with respect to the wall or frame in which they are mounted comprising, in combination, a base member adapted to be secured to the wall or frame, a plate-like member adapted to be secured to the door, a plurality of parts each having an aperture therein and each 15 rotatably supported by said base member for rotation about an axis at right angles to the axis of said aperture therein and forming therewith a single hinge unit, said plurality of parts extending in a general direction away from the 20 plane of said wall or frame, means comprising hinge pin means engageable in said apertures when the latter are appropriately alined relative thereto for pivotally connecting said plate-like member to said plurality of parts to swing about 25 the axis of said apertures when alined, and means responsive to rotational movement of said plurality of parts, each in increments of 180° , relative to said base member for moving said parts each to the same extent, for each increment 30 of rotational movement, in a direction toward or away from said wall or frame and thereby alter the spacing of the axis of pivoting from the plane of said wall or frame while maintaining alinement of the axes of said apertures. 35

SIGURD BRANTINGSON.
